United States Patent Office

Des. 182,257
Patented Mar. 4, 1958

182,257

VACUUM CLEANER OR SIMILAR ARTICLE

Bertrand N. Trombley, Birmingham, Mich., assignor to
Kingston Products Corporation, Kokomo, Ind., a cor-
poration of Indiana

Application May 8, 1957, Serial No. 46,058

Term of patent 3½ years

(Cl. D9—2)

FIG. 1

FIG. 3

FIG. 2

Figure 1 is a perspective view of the vacuum cleaner or similar article, showing my new design;

Figure 2 is a side elevational view thereof; and

Figure 3 is a top plan view thereof.

I claim:

The ornamental design for a vacuum cleaner or similar article, as shown.
